CENTRIFUGAL PUMP

Application filed February 2, 1931. Serial No. 512,863.

This invention relates to a centrifugal pump and particularly to means embodied therein for protecting a stuffing box against the action of liquid at high temperature and pressure.

When centrifugal pumps are used for pumping hot liquids, for example, pre-heated water when acting as boiler feed pumps, leakage ordinarily subjects the packing about the impeller shaft to very high pressures and temperatures. While soft packing of the type generally considered desirable can satisfactorily take care of pressures slightly in excess of 300 pounds per square inch at ordinary temperatures, it is rapidly destroyed when subjected to pressures of higher degree or pressures of lower degree when the temperature is high. Under some circumstances, for example, the suction chamber of a multistage boiler feed pump may contain water having a temperature above 500° F. and a pressure as high as 800 pounds per square inch. The soft packing is unable to withstand this pressure or temperature.

It is the broad object of the present invention therefore to provide a means for protecting this suitable type of packing against the combined action of high temperatures and pressures existing both at the intake and discharge ends of centrifugal pumps, particularly of the multistage type.

Other objects relating to details of construction will be apparent from the following description read in conjunction with the accompanying drawings in which:

Fig. 1A is a vertical sectional view, partly diagrammatic in form, of the lefthand suction end of a multistage centrifugal pump; and

Fig. 1B is a similar view of the righthand discharge end of the same.

The illustrated pump comprises a casing 2 preferably formed in upper and lower sections in the usual fashion in which is journaled the impeller shaft 4 through the medium of suitable bearings (not shown) located at the ends of the casing. At each end where the shaft passes through the casing, it is provided with a sleeve 6 passing through a suitable stuffing box containing soft pack-

ing 8 compressed into position within the stuffing box wall 10 by means of a gland 12, the packing being backed up by an annular member 14 engaging a portion of the casing. As will be seen from the drawing, this construction is duplicated at the two ends.

At the intake and discharge ends there are respectively provided labyrinthine packings 16 and 18 providing tortuous passages through which liquid may leak only with considerable drop in pressure. At the left-hand end of the pump inwardly of the labyrinthine packing 16 is located the suction chamber 20 from which liquid is taken by the first-stage impeller 22 and passed thereby in the usual fashion through the series of impellers, finally being discharged by the impeller 24 of the last stage into the discharge chamber 26. Leakage from the discharge chamber is controlled to some extent by the annular member 28 fixed to the shaft and running between an annular ring at its inner side and an adjustable shim 30 at its outer side. Outside of the adjustable shim is a chamber 32 receiving leakage passing the member 28, this chamber 32 being connected through a balancing pipe 34 with the suction chamber 20. The labyrinthine packing 18 permits leakage from the chamber 32 with a considerable drop in pressure.

Outside the labyrinthine packing 16 is an annular chamber 36 surrounding the shaft and bounded on its outer side by the member 14. A similar chamber 38 on the discharge end of the pump is outwardly bounded by the duplicate member 14. Pipes 40 and 42 connect the chambers 36 and 38 to each other and to a relief valve 44 which may be set to pass liquid whenever the pressure exceeds a predetermined amount.

Leading from the discharge of the first stage impeller 22 is a pipe 46 serving to pass liquid to a cooler 48 in which the temperature may be dropped from the region of up to 550° F. to 212° F. or lower. The liquid from the cooler passes through pipe 50 to a regulating valve 52 and thence through pipes 54 and 56 to annular chambers 58 and 60 surrounding the sleeves 6 and formed in the corresponding members 14. Restricted

leakage from chambers 58 and 60 to chambers 36 and 38 is permitted.

Leading from chambers 60 and 38 are pipes 62 and 64 communicating with the upper and lower sides respectively of a diaphragm within a housing 66, which diaphragm is connected to a valve controlling the flow through the regulating valve 52. A spring 68 normally urges the valve member within the 10 valve 52 to unseated position in opposition to pressure exerted through pipe 62 upon the top of the diaphragm. A vent 70 may be provided to permit the discharge of liquid from the pipe 62.

15 The pressures in chambers 20 and 32 are substantially equal. Similarly the pressures in chambers 36 and 38 are substantially equal by reason of their interconnection through pipes 40 and 42. The pressures in 58 and 60 20 are also maintained substantially equal through the connections 54 and 56. Accordingly, it will be seen that the operations of the improved packing protecting means are similar at each end of the pump.

25 In the operation of the device the pressures and temperatures in the chamber 20 may be quite high. For example, the pressure may be in excess of 800 pounds per square inch and the temperature above 500° F. By 30 reason of the labyrinthine packing 16, as leakage occurs from the chamber 20 into the chamber 36, the pressure will be very considerably reduced, the effective pressure being controlled by the setting of the relief 35 valve 44 which may, for example, considering a pressure of 800 pounds per square inch in the chamber 20, be set to discharge at 300 pounds per square inch. The temperature within chamber 36 however will be substantially as high as that in the chamber 20. Accordingly, while the pressure is of a suitable amount which would not harm the packing, the temperature is still excessive and provision is therefore made to prevent the application of liquid at this high temperature 40 to the soft packing.

45 For this purpose the discharge from the first stage through pipe 46 is cooled by means of cooler 48 to a suitable low temperature, 50 for example, around 200° F. and is then passed through the regulating valve 52 which will effect a reduction of pressure so that the liquid entering chamber 58 through pipe 54 55 will have a low temperature and a pressure just slightly in excess of the pressure in chamber 36. The regulating valve automatically takes care of this since the top of the diaphragm is connected to the chamber 58 and the bottom of the diaphragm to the 60 chamber 36 and the spring 68 adjusted so as to require a pressure in chamber 58 in excess of the pressure in chamber 36 by some predetermined amount. For example, the spring 68 may represent a difference in pressure of 25 pounds per square inch so that if 65

the pressure in chamber 36 is 300 pounds the pressure in chamber 58 will be maintained about 325 pounds by reason of the fact that the valve 52 will remain open until such larger pressure occurs.

70 By reason of the fact that the pressure in chamber 58 is greater than that in 36, a flow of liquid from the former to the latter will occur, thus preventing the high temperature liquid in chamber 36 from reaching the packing. 75

80 While the description above has been made with reference to the lefthand end of the pump, it will be obvious that a similar condition exists simultaneously at the righthand end, the cooler and controls 44 and 52 functioning with respect to both ends. The equalizing or balancing pipe 34 insures similar initial conditions.

85 It will be clear that the cooling water may be provided from an outside source as, for instance, by means of a separate cold-water pump.

90 What I claim and desire to protect by Letters Patent is:

95 1. A centrifugal pump including a casing having intake and discharge passages; a shaft mounted in the casing; packing for the shaft; impeller means carried by the shaft; a chamber about the shaft adjacent the impeller means arranged to contain liquid at high temperature and pressure; a second chamber about the shaft between the packing and first chamber; means providing communication between the two chambers and operable to reduce the pressure of liquid flowing from the first to the second; a third chamber about the shaft between the packing and the second chamber; and means for supplying the third chamber with liquid at low temperature and at a pressure in excess of the pressure in the second chamber, said last named means including a conduit between the impeller means and the third chamber, and pressure-responsive means for controlling flow in said conduit to maintain the pressure of liquid in the third chamber higher than the pressure of liquid in the second chamber. 100

105 2. A centrifugal pump including a casing having intake and discharge passages; a shaft mounted in the casing, packing for the shaft; impeller means carried by the shaft; a chamber about the shaft adjacent the impeller means arranged to contain liquid at high temperature and pressure; a second chamber about the shaft between the packing and first chamber; means providing communication between the two chambers and operable to reduce the pressure of liquid flowing from the first to the second; a third chamber about the shaft between the packing and the second chamber; and means for supplying the third chamber with liquid at low temperature and at a pressure in excess of the pressure in the second chamber, said last named means in- 110

cluding a conduit between the impeller means and the third chamber, and means for controlling flow in said conduit to maintain the pressure of liquid in the third chamber higher than the pressure of liquid in the second chamber, and connections between the flow-controlling means and the second and third chambers arranged to automatically actuate the flow controlling means in accordance with the pressures in the second and third chambers.

3. A centrifugal pump including a casing having intake and discharge passages; a shaft mounted in the casing, packing for the shaft; impeller means carried by the shaft; a chamber about the shaft adjacent the impeller means arranged to contain liquid at high temperature and pressure; a second chamber about the shaft between the packing and first chamber; means providing communication between the two chambers and operable to reduce the pressure of liquid flowing from the first to the second; a third chamber about the shaft between the packing and the second chamber; and means for supplying the third chamber with liquid at low temperature and at a pressure in excess of the pressure in the second chamber, said last named means including a conduit between the impeller means and the third chamber, means for cooling liquid passing through the conduit, and pressure responsive means for controlling flow in said conduit to maintain the pressure of liquid in the third chamber higher than the pressure of liquid in the second chamber.

4. A centrifugal pump including a casing having intake and discharge passages; a shaft mounted in the casing, packing for the shaft; impeller means carried by the shaft; a chamber about the shaft adjacent the impeller means arranged to contain liquid at high temperature and pressure; a second chamber about the shaft between the packing and first chamber; means providing communication between the two chambers and operable to reduce the pressure of liquid flowing from first to the second; a third chamber about the shaft between the packing and the second chamber; and means for supplying the third chamber with liquid at low temperature and at a pressure in excess of the pressure in the second chamber, said last named means including a conduit between the impeller means and the third chamber, means for cooling liquid passing through the conduit, and means for controlling flow in said conduit to maintain the pressure of liquid in the third chamber higher than the pressure of liquid in the second chamber, and connections between the flow-controlling means and the second and third chambers arranged to automatically actuate the flow-controlling means in accordance with the pressures in the second and third chambers.

5. A centrifugal pump including a casing

having intake and discharge passages; a shaft mounted in the casing; packing for the shaft; impeller means carried by the shaft; a chamber about the shaft adjacent the impeller means arranged to contain liquid at high temperature and pressure; a second chamber about the shaft between the packing and first chamber; means providing communication between the two chambers and operable to reduce the pressure of liquid flowing from the first to the second; means for relieving pressure in the second chamber; a third chamber about the shaft between the packing and the second chamber; and means for supplying the third chamber with liquid at low temperature and at a pressure in excess of the pressure in the second chamber.

6. A centrifugal pump including a casing having intake and discharge passages; a shaft mounted in the casing; packing for the shaft; impeller means carried by the shaft; a chamber about the shaft adjacent the impeller means arranged to contain liquid at high temperature and pressure; a second chamber about the shaft between the packing and first chamber; means providing communication between the two chambers and operable to reduce the pressure of liquid flowing from the first to the second; means for relieving pressure in the second chamber; a third chamber about the shaft between the packing and the second chamber; and means for supplying the third chamber with liquid at low temperature and at a pressure in excess of the pressure in the second chamber, said last named means including a conduit between the impeller means and the third chamber, means for cooling liquid passing through the conduit, and pressure-responsive means for controlling flow in said conduit to maintain the pressure of liquid in the third chamber higher than the pressure of liquid in the second chamber.

7. A centrifugal pump including a casing having intake and discharge passages; a shaft mounted in the casing; multistage impeller means carried by the shaft; packing arrangements on opposite sides of the impeller means, each of said packing arrangements including packing for the shaft, a chamber about the shaft adjacent the impeller means arranged to contain liquid at high temperature and pressure, a second chamber about the shaft between the packing and first chamber, means providing communication between the two chambers and operable to reduce the pressure of liquid flowing from the first to the second, and a third chamber about the shaft between the packing and the second chamber; and means for supplying each of the third chambers with liquid at low temperature and at a pressure in excess of the pressure in its corresponding second chamber, said last mentioned means including a conduit between a

low pressure stage of the impeller means and both of the third chambers, and pressure responsive means for controlling flow in said conduit to maintain the pressure of liquid in each of the third chambers higher than the pressure of liquid in its corresponding second chamber.

8. A centrifugal pump including a casing having intake and discharge passages; a shaft mounted in the casing; multistage impeller means carried by the shaft; packing arrangements on opposite sides of the impeller means, each of said packing arrangements including packing for the shaft, a chamber about the shaft adjacent the impeller means arranged to contain liquid at high temperature and pressure, a second chamber about the shaft between the packing and first chamber, means providing communication between the two chambers and operable to reduce the pressure of liquid flowing from the first to the second, and a third chamber about the shaft between the packing and the second chamber; an equalizing connection between the first mentioned chambers; and means for supplying each of the third chambers with liquid at low temperature and at a pressure in excess of the pressure in its corresponding second chamber.

9. A centrifugal pump including a casing having intake and discharge passages; a shaft mounted in the casing; multistage impeller means carried by the shaft; packing arrangements on opposite sides of the impeller means, each of said packing arrangements including packing for the shaft, a chamber about the shaft adjacent the impeller means arranged to contain liquid at high temperature and pressure, a second chamber about the shaft between the packing and first chamber, means providing communication between the two chambers and operable to reduce the pressure of liquid flowing from the first to the second, and a third chamber about the shaft between the packing and the second chamber; an equalizing connection between the first mentioned chambers; and means for supplying each of the third chambers with liquid at low temperature and at a pressure in excess of the pressure in its corresponding second chamber, said last mentioned means including a conduit between a low-pressure stage of the impeller means and both of the third chambers, and means in said conduit for maintaining the pressure of liquid in each of the third chambers higher than the pressure of liquid in its corresponding second chamber.

10. A centrifugal pump including a casing having intake and discharge passages; a shaft mounted in the casing; packing for the shaft; impeller means carried by the shaft; a chamber about the shaft adjacent the impeller means arranged to contain liquid at high temperature and pressure; a second

chamber about the shaft between the packing and first chamber; means providing communication between the two chambers and operable to reduce the pressure of liquid flowing from the first to the second; a third chamber about the shaft between the packing and the second chamber; and means for supplying the third chamber with liquid at low temperature and at a pressure in excess of the pressure in the second chamber, said last named means including a conduit between the impeller means and the third chamber, and means responsive to differences in pressure in the second and third chambers for controlling flow in said conduit to maintain the pressure of liquid in the third chamber higher than the pressure of liquid in the second chamber.

11. A centrifugal pump including a casing having intake and discharge passages; a shaft mounted in the casing; multistage impeller means carried by the shaft; packing arrangements on opposite sides of the impeller means, each of said packing arrangements including packing for the shaft, a chamber about the shaft adjacent the impeller means arranged to contain liquid at high temperature and pressure, a second chamber about the shaft between the packing and first chamber means providing communication between the two chambers and operable to reduce the pressure of liquid flowing from the first to the second, and a third chamber about the shaft between the packing and the second chamber; and means for supplying each of the third chambers with liquid at low temperature and at a pressure in excess of the pressure in its corresponding second chamber, said last mentioned means including a conduit between a low-pressure stage of the impeller means and both of the third chambers, and means responsive to differences in pressure in the second and third chambers for controlling flow in said conduit to maintain the pressure of liquid in each of the third chambers higher than the pressure of liquid in its corresponding second chamber.

12. A centrifugal pump including a casing having intake and discharge passages; a shaft mounted in the casing; packing for the shaft; impeller means carried by the shaft; a chamber about the shaft adjacent the impeller means arranged to contain liquid at high temperature and pressure; a second chamber about the shaft between the packing and first chamber; means providing communication between the two chambers and operable to reduce the pressure of liquid flowing from the first to the second; a third chamber about the shaft between the packing and the second chamber; means for supplying the third chamber with liquid at low temperature and at a pressure in excess of the pressure in the second chamber; and means responsive to

differences in pressure in the second and third chambers for controlling the supplying means to maintain the pressure of liquid in the third chamber higher than the pressure of liquid in the second chamber.

In testimony of which invention, I have hereunto set my hand, at Trenton, New Jersey, on this 30th day of January, 1931.

ARVID PETERSON.
